Application April 16, 1953, Serial No. 349,239

Claims priority, application Germany April 24, 1952

7 Claims. (Cl. 103—87)

This invention is concerned with a portable pump comprising a pump unit provided with a propeller element, a motor disposed outside said pump-unit, and means for removably connecting said motor with the pump-unit.

Prior pumps had the disadvantage, that the exchange of the motor or pump-unit was comparatively difficult and afforded much work. According to the invention the disadvantage has been avoided by connecting the shaft of the motor, disposed outside the pump-unit, with the shaft of the propeller element by a simple clutch and by connecting the motor-housing, which forms the upper part of the pump, by means of a cylindrical fastening of the bayonet type, with a hollow cylindric part of the riser conduit surrounding the shaft and the propeller element. The new structure separates the motor and the pump-unit so that the transferred liquid cannot affect the motor.

Parts of the pump unit may be made of suitable thermoplastic artificial material which is not affected by chemicals. Such material can very well be used, because the heat developed by the motor will not affect it due to the length of the riser conduit. The pump according to the invention may therefore be used for handling liquids in the chemical industry. Pump-units made of physiologically harmless artificial material can also be employed in other industries, for example, dairies.

The invention will now be described with reference to examples shown in the accompanying drawings, wherein:

Fig. 1 shows an elevational view of an electric motor to be used as a driving motor;

Fig. 2 shows in similar representation an internal combustion motor for driving the pump-unit;

Fig. 3 shows a pump-unit partly in longitudinal section;

Fig. 4 is a longitudinal section of a pump-unit with a pump-unit shaft moving in a supporting tube;

Fig. 5 is a part sectional view of a pump-unit without supporting tube for the pump-unit shaft;

Fig. 6 shows a part sectional view of a pump-unit with a feed screw;

Fig. 7 shows a part sectional view of a pump-unit with a flexible riser conduit and flexible pump shaft;

Fig. 8 indicates a pump-unit made as a stirrer and removed from the riser conduit; and

Fig. 9 indicates a measuring device disposed at the discharge of the pump-unit.

The electric motor shown in Figure 1 has a fastening 2 serving as connection to the pump-unit and according to the invention provided with a flange 1 forming a handle. Out of the fastening 2 rises the motor driving shaft provided with a clutch part 3. The flange 1 not only facilitates the handling of the pump, it is also possible to flange the pump unit easily, when mounting at a permanent place is desired.

The electric motor may be operated from a suitable current supply including a battery, for example, the battery of a vehicle. The rating of the motor will depend

2

upon the transferring capacity in accordance with the viscosity of the liquid to be handled.

The internal combustion motor indicated in Fig. 2, which can also be a small fuel motor, has also a flange 5 1 and a cylindric fastening 2 whilst the driving shaft has a clutch part 3. The driving shaft is operated by the crank shaft of the motor over a driving gear with the necessary gear-ratio. A driving gear may also be employed in the structure shown in Fig. 1.

10 The use of a combustion motor makes the working of the pump independent of a commercial current supply.

The construction of the upper part of a pump-unit, to be connected with the driving motor, is apparent from 15 Figs. 3 to 9. The hollow cylindrical part 4 of the pump-unit, takes up the cylindrical fastening 2 of the motor and is latched by a bayonet pin 6. On mounting the motor its clutch part 3 contacts the clutch part 5 mounted on the upper end of the riser conduit.

20 The pump-unit shown in Fig. 4 has an upper housing part 7 with a hollow cylindrical part 4 just as in Fig. 3. The riser conduit 11 can be removed from the part 7, e. g. by fastening it by means of joint 12. The easy disconnection of the riser conduit from the upper housing part 25 of the pump-unit facilitates the mounting and allows a complete cleaning of the inner part of the pump. The riser conduit 11 has on its top a discharge 19.

The upper part 7 of the pump unit takes up in a centralized bore the upper bearing as well as the gasket 30 10 belonging to it. The shaft 16 of the pump-unit moves according to the invention, in a supporting pipe 8 fitted in the riser conduit 11, if necessary filled with damping liquid, and has at its lower end one or several exchangeable propeller elements 18. The supporting pipe 8 is fastened 35 on its upper end by the upper housing part 7, while its lower end carries the pump-element support 13. The pump-element support 13 carries the lower bearing 14 of the shaft 16 and the gaskets 15 belonging to them. The shaft 16 emerges from the support 13 carrying at 40 its free end exchangeable propeller elements 18.

According to a further feature of the invention the lower part of the riser conduit 11 is provided with a suction slot 20, covered by an exchangeable strainer plate 21. The propeller element reaches into the lower part 45 of the pump-unit, bearing the suction slot, so that the pump is able to transfer liquid as long as the riser conduit dips thereinto. The suction slot is protected against ingress of small parts, which might lead to clogging of the pump, by the strainer plate which may be fixed or exchangeable.

The support 13 for the propeller element is fitted in the lower part of the riser conduit 11 and mounted on the lower end of the supporting pipe 8 thus also advantageously serving for conducting the transferring liquid. 55 If the riser conduit has a greater length the swinging of the pump unit shaft can be suppressed not only by a damping liquid but also by one or several support bearings which are arranged inside the conduit.

From Fig. 5 it will be seen that the shaft 26 of the pump-unit moves in the transferring liquid without supporting tube. The pump-element support 23, which also serves for conducting the liquid takes up the lower bearing 24 of the shaft of the pump-unit together with the gasket 25 and is interrupted by the suction slot 27. The support 23 for the propeller element is fixed after the riser conduit has been mounted, by nuts or other means in such conduit. If the riser pipe has a great length, the corresponding longer shaft of the pump-unit may be journaled in one or several bearings 28.

The pump-unit shaft 29 as shown in Fig. 6 is provided for part of its length with a feed screw. The bottom

closure 30 of the riser conduit 31 takes up the lower bearing 32 with the gaskets 33. The suction slots 34 are near the lower end of the conduit 31 or in the bottom closure as shown at 35.

As shown in Fig. 7, the riser conduit may be a flexible tube and drive shaft may also be flexible. On the housing part 37 of the pump-unit, which can be constructed as is shown in the previous embodiments, is provided the flexible tube forming the riser conduit 36. Correspondingly the pump-unit shaft 41 is also constructed as flexible shaft, and is protected against the transferring liquid by the tube 42. The lower end 40 of the conduit 36 is inflexible for a short length, in order to be able to fasten the support of the pump-element 38. The pumping wheel 39 driven by shaft 41 is protected against mechanical damage and fits inside the support 38. The flexible conduit of this pump unit allows the drawing off of liquids from relatively inaccessible places.

The example Fig. 8 shows the pump-unit transformed into a stirrer or emulsifier, by dismounting the riser conduit and replacing the pump wheel or wheels by one or several stirring wheels 43.

According to Fig. 9, there is a calibrated receptacle 44 provided with a tap 46 connected with the discharge 19 of the pump unit, which takes up any desired quantity of liquid determined by the position of the overflow slot regulated by the lever 45. When the desired quantity of liquid is passed, the overflowing liquid stops the driving motor automatically. It is advantageous to have a transparent measuring receptacle so as to be able to read the scale provided thereon.

The last described embodiment is especially advantageous for installations where a fixed quantity of liquid is always to be handled, e. g. 0.5 litre, 1.0 litre, 1.5 litre, etc. After switching on the pump, the receptacle 44 fills up to the regulated overflow slot. The overflowing liquid flows by means of an overflow conduit back into the tank and causes a switch to operate, which stops the tank-pump automatically. The measured liquid is discharged by the tap 46.

In order to transfer continually, all overflow slots are closed by the lever 45 so that the transferred liquid can only flow off at the tap 46. The overflow slots determine the quantities to be discharged. For quantities lying between the fixed ones on the scale, the next higher quantity marked on the lever 45 is taken. After the automatic stopping of the tank-pump the lever is regulated in a manner that the overflow slot corresponding to the next lower quantity works like a tap, so that the surface of the liquid can be let down to the desired quantity.

Changes may be made within the scope and spirit of the appended claims.

I claim:

1. A portable pump adapted to be manipulated by hand with respect to a liquid to be processed thereby, comprising a tubular riser conduit having the configuration of a pipe with uniform outer diameter throughout its length, one end of said riser conduit to be immersed in the liquid which is to be processed, discharge means extending from said riser conduit in the vicinity of the other end thereof, a drive shaft axially disposed in said riser conduit and extending longitudinally therewithin, a propeller element carried by said drive shaft in the vicinity of the end of said riser conduit which is to be immersed in the liquid to be processed, said propeller element being axially removable from said drive shaft, inlet openings formed in said riser conduit at the end thereof which is adjacent said propeller element, means for rotatably supporting said drive shaft within said riser conduit, a motor for driving said drive shaft, a housing for said motor which is manually removably inserted thereinto, means for axially manually removably mounting

said housing on said riser conduit at the end thereof which is adjacent said discharge means, the shaft of said motor extending axially centrally of said riser conduit when the motor is inserted in said housing and the latter 5 mounted on said riser conduit, and clutch means carried by said motor shaft for engagement, within said housing, with cooperating clutch means carried by said drive shaft so as to connect said motor shaft in driving relationship with said drive shaft solely responsive to manual insertion of said motor while effecting release of said driving relationship solely responsive to manual removal of said motor.

2. A structure and cooperation of parts according to claim 1, comprising a perforated strainer plate disposed in said riser conduit adjacent the inlet openings formed therein.

3. A structure and cooperation of parts according to claim 1, comprising a tubular shell surrounding said drive shaft within said riser conduit, said tubular shell 20 containing damping fluid, and means for connecting said shell with said housing.

4. A structure and cooperation of parts according to claim 1, comprising means carried by said motor and forming a handle therefor to facilitate manipulation thereof incident to insertion of the motor into and removal thereof from said housing.

5. A structure and cooperation of parts according to claim 1, comprising means, disposed within said riser conduit in the vicinity of the end thereof which is to be 30 immersed in the liquid to be processed, for rotatably supporting said drive shaft at a point axially inwardly spaced from said propeller element.

6. A structure and cooperation of parts according to claim 1, comprising tubular means, disposed within said riser conduit at the end thereof which is to be immersed in the liquid to be processed, means for rotatably journaling said drive shaft in said tubular means at a point axially inwardly spaced from said propeller element, said tubular means forming a skirt surrounding said propeller element.

7. A structure and cooperation of parts according to claim 1, comprising a tubular shell surrounding said drive shaft within said riser conduit throughout the length of said drive shaft, bearing means in said shell for rotatably journaling said drive at a point axially inwardly spaced from said propeller element, said shell forming a skirt extending therefrom and surrounding said propeller element, the opposite end of said shell being connected with said housing, said shell forming with said drive shaft and said housing a unit which is manually removable from said riser conduit.
